WRITING IMPLEMENT HOLDER FOR A TELEPHONE

Joseph Rossman, 76 Paulison, Passaic, N.J.

Filed May 19, 1964, Ser. No. 80,051

Term of patent 14 years

(Cl. D26—14)

I claim:

The ornamental design for a writing implement holder for a telephone, substantially as shown.
